United States Patent Office

Des. 205,564
Patented August 16, 1966

205,564

AIRPLANE

Robert W. Allred, Bellevue, and Fred W. Clayton, Maple Valley, Wash., assignors to The Boeing Company, Seattle, Wash., a corporation of Delaware

Continuation of design applications Ser. No. 82,737 and Ser. No. 82,746, Nov. 23, 1964. This application July 26, 1965, Ser. No. 86,861

Term of patent 14 years

(Cl. D71—1)

Des. 205,564

PAGE 5

Fig. 7

Fig. 8

FIGURE 1 is a three-quarter front perspective view taken from the top.

FIGURE 2 is a three-quarter rear perspective view taken from the bottom.

FIGURES 3, 4 and 5 are front, rear and side elevation views respectively.

FIGURE 6 is a top plan view of the new airplane design.

FIGURE 7 is a three-quarter front perspective view of a modified form of the airplane shown in FIGURE 1.

FIGURE 8 is a three-quarter rear perspective view taken from the bottom.

FIGURES 9, 10 and 11 are front, rear and side elevation views respectively.

FIG. 12 is a top plan view thereof.

This is a continuation of applications Serial Nos. D. 82,737 and D. 82,746 both filed November 23, 1964, and now abandoned.

The dominant features of our design are shown in solid lines in the drawings.

We claim:

The ornamental design for an airplane, substantially as shown and described.
